CLAIM

The ornamental design for sheet material with camouflage pattern for day and night use, as shown and described.

DESCRIPTION

FIG. 1 is a front view of sheet material with camouflage pattern for day and night use showing the new design;

FIG. 2 is a front view of sheet material with camouflage pattern for day and night use according to another embodiment that is closely related to that shown in FIG. 1;

FIG. 3 is a front view of sheet material with camouflage pattern for day and night use according to another embodiment that is closely related to that shown in FIG. 1;

FIG. 4 is a front view of sheet material with camouflage pattern for day and night use according to another embodiment that is closely related to that shown in FIG. 1;

FIG. 5 is a front view of sheet material with camouflage pattern for day and night use according to another embodiment that is closely related to that shown in FIG. 1;

FIG. 6 is a front view of sheet material with camouflage pattern for day and night use according to another embodiment that is closely related to that shown in FIG. 1; and,

FIG. 7 is a front view of sheet material with camouflage pattern for day and night use according to another embodiment that is closely related to that shown in FIG. 1.

In the drawings, the oblique line shading depicts surfaces that are reflective in low light conditions.
